UNITED STATES PATENT OFFICE

JOHN E. CASTER, OF CINCINNATI, OHIO, ASSIGNOR TO CINCINNATI GRINDERS INCORPORATED, OF CINCINNATI, OHIO, A CORPORATION OF OHIO

LONG BAR GRINDER

Application filed May 20, 1929. Serial No. 364,442.

This invention relates to improvements in grinding machinery and more especially that type of machinery commercially known as centerless grinders.

One of the principal objects of the present invention is the provision of a grinding machine of the centerless type particularly adapted for use in the grinding of long bars, tubes and similar articles with extreme accuracy.

A further object of the invention is the provision of an improved work supporting mechanism capable of application to commercial centerless grinders which will facilitate the accurate positioning and supporting of an elongated work piece during its introduction to, passage through and removal from the grinding throat whereby extreme accuracy of product will be insured.

A further object of the invention is the provision of mechanism facilitating the accurate relative adjustment of the several work supporting portions on the device to insure proper axial alignment of the projecting terminal portions of the work with the grinding throat and thus prevent impairment of accuracy of the final product due to radial displacement of the work in any direction during the grinding.

Other objects and advantages of the invention should be readily apparent by reference to the following specification considered in conjunction with the accompanying drawings and it will be understood that any modifications in the specific structural details hereinafter disclosed, may be made within the scope of the appended claims without departing from or exceeding the spirit of the invention.

Figure 1 is a perspective view of the machine embodying the invention.

Figure 2 is a view of the parts at the grinding throat with regulating wheel unit removed and portions broken away.

Figure 3 is a section as on line 3—3 of Figure 1.

Figure 4 is a vertical section illustrating the work rest clamp mechanism as on the line 4—4 of Figure 2.

Figure 5 is a section as on line 5—5 of Fig-

ure 2 illustrating one of the inner work supporting members, and

Figure 6 is a horizontal section on the line 6—6 of Figure 2 illustrating the adjusting and securing means for the work rest blade. 55

In the drawings the numeral 10 designates the bed of a centerless grinder of conventional form having the ways 11 for the main slide 12 which in turn is provided with ways 13 for the regulating wheel unit 14. 60

Disposed at the opposite end of the bed 10 is the head 15 by which is rotatably supported the grinding wheel 16. This latter in accordance with standard practice is driven at a high or grinding rate of speed 65 with its operative surface moving downward or in a clock-wise direction as indicated by the arrow in Figure 4 for proper removal of stock from the work piece.

Located on the grinding wheel unit and in 70 opposition to the grinding wheel is the control or regulating wheel 17 also rotating in a clock-wise direction to cause its inner operative surface to move upward. This wheel is driven at a slow rate of speed having a 75 wearing friction contact with the work piece for determining the rate of rotation thereof.

In addition, this wheel is preferably axially tilted to create a feed component producing a traverse or feeding movement of the 80 work through the grinding throat provided between grinding and regulating wheels. The slide 12 forms a support for the work rest bracket unit 18 having the terminal socketed portions 19 to receive the support 85 bars or tubes 20. As the construction at the front and rear of the machine is the same a description of either will suffice for a proper understanding of both.

Socket 19 is preferably kerfed or split as at 90 21 and provided with webs 22 drawn together as by clamp bolt 23 to secure member 20 in position. Additionally, to prevent rotative or twisting movement of member 20, use may be made of suitable locking means such as 95 bolt 23a. The work rest bracket 18 is centrally slotted at 24 to receive plate 25 bearing angle top work rest blade 26 for supporting the work piece 27 within the grinding throat.

Plate 25 has sockets as at 28 to receive balls 100

- 29 abutted by the work rest blade adjusting plungers 30 sliding in guides 31 of member 18 and having bevelled lower ends riding on cam faces 32 of the adjusting slide 33. This slide is urged in one direction by compression spring 34 and is adjustable in the opposite direction by screw 35. This adjustment under the influence of the screw forces plungers 30 and thus the work rest blade 26 upward to vary the height of the angle top of the blade and thus the position of the axis of the work piece riding thereon with respect to the axes of the grinding and regulating wheels.
- 15 To facilitate securing of the work rest blade in desired vertically adjusted position use is made of the clamp arms 36 intermediately pivoted as at 37 and coupled by cross bar 38 which forms a power equalizer for distribution of the clamping pressure. The clamping itself is effected through block 39 shiftable by cam plunger 40 and pressure screw 41 as it will be readily understood by reference to Figure 6.
- 20 This particular mechanism is capable of employment when the grinder is to be used for ordinary short work pieces and in the absence of the outer supporting members hereinafter described, though being particularly advantageous when it is necessary to line up both the work rest blade and such outer supporting members in definite relationship one to the other.
- 25 The bracket 18 is additionally provided with a slotted guide portion at 42 for support 43 bearing trunnion 44 for the work supporting roller 45 which is adapted to be so positioned as to contact with the work piece 27 in the plane of contact of the angle top 40 of the work rest blade with the work piece.
- 30 To facilitate adjustment of roller 45 to this exact position, use is made of the adjusting screw 46 abutting at its lower end the bracket 18 and secured in adjusted position as by lock nut 47.
- 35 Tightening of bolts 48 firmly secures member 43 in its proper position of vertical adjustment.
- 40 In the production of work pieces by the centerless method it is customary to support the work piece on a suitable member such as the angle top work rest blade here shown in connection with a regulating wheel member backing up the work and urging same in the direction of the grinding wheel. The angle top work rest functions to produce a slight rising or upward movement of the work piece in the grinding throat when minute irregularities or the like on the work engage the regulating wheel thus minimizing the depth of opposite cut taken by the grinding wheel. The work rest and regulating wheel together therefore, jointly form the determinants of position of the work at all times with respect to the grinding wheel and the position of path and of the work as determined thereby is of prime importance.
- 45 In the structure the roller 45 exteriorly supporting the work presents its surface in substantial correspondence with that of the surface of the work rest blade by its free rotation releasing the blade of the pressure of weight of the outer portion of the work piece and preferably being at a slight angle to complement the feeding action of the regulating wheel. For proper retention of the work in engagement with roller 45 in correspondence with the position of engagement with the portion of the work being operated upon with the work rest, use is made of a second supporting roll 49 rotatably mounted on bracket 50 adjustably secured to bell crank arm 51 as by bolt 52. This bell crank arm is pivoted at 53 to a support 54 on the bracket 18 and is adjustably maintained in position by elevating screw 55 and clamp screw 56 as indicated in Figure 5.
- 50 This roll is also disposed with its axis at an angle to both rotatable support and produce feeding movement of the work as the latter is rotated and is adjusted to contact with a point on the work in correspondence with the point in engagement of the regulating wheel surface therewith.
- 55 In the production of work of considerable length the individual outboard supports just described are insufficient to fully position and support the outer portions of the work and prevent whipping thereof.
- 60 The additional outer support members comprise a series of similar units mounted on the members 20. These units as illustrated in detail in Figures 1 and 3 comprise a split collar member 55 adapted to be clamped to member 20 as by bolt 56. This collar has an upstanding arm 57 with an adjustable section 58 bearing a roller 59 designed to be aligned with the work rest blade and roller 45 as respects its contact point with the work piece 27. Such adjustment is facilitated by screw 60 and clamp bolts 61 retaining the roller bearing section in its adjusted position.
- 65 Collar 55 is preferably secured against rotation on member 20 by lag screw 62 so that arm 57 will at all times extend in a parallel vertical plane with that of the work rest blade.
- 70 Disposed immediately adjacent each collar unit 55 is a second split clamp 63 securable as by bolt 64 and having a substantially radially projecting arm 65 provided with an adjustable head 66 bearing the work engaging tilted roller 67 designed to be accurately lined with the work contacting point of the regulating wheel and roller 49.
- 75 To facilitate radial adjustment of the position of arm 64 with respect to upright 57, collar 55 has its web 68 socketed as at 69 to engage the adjusting screw 70 carried by the overlying laterally projecting lug 71 on collar 130

63. Upon loosening of clamp collar 63 same may be rotated about member 20 to an outward position limited and determined by engagement of screw 70 with the fixed non-
5 rotatable collar 55 and in this manner an extremely small and accurate positioning of the arm 64 of each unit and thus of the supporting roller 67 carried by the arm is attained.

In the operation of the aforesaid mechanism the bracket unit 18 with its several associated parts is mounted and suitably secured on the main slide 12 of the machine and the several parts so that the work rest blade and the series of outer work supporting units will equally support the work piece against axial deflection due for example, to weight of the overhanging portion thereof.

At the same time the regulating wheel unit 14 is adjusted to properly engage the work in opposition to the work rest by movement on ways 13 and the several rolls 49 and 67 adjusted to correspondingly engage the outer portion of the work and prevent its lateral deflection in the direction of the regulating wheel or away from the grinding wheel.

The several parts having been thus adjusted regulating wheel unit 14 is locked to slide 12 in definite relation to the work rest bracket and parts carried thereby. The slide 12 with all associate parts is then fed toward the grinding wheel as by manipulation of control wheel 73 to insure proper stock removal from the work piece and the work is axially advanced through the machine by the combined action of the feed component of the regulating wheel and that of the individual work supporting rollers and a uniform grinding from end to end of the work is effected.

10 I claim:—

1. The combination with a centerless grinder including opposed grinding and regulating wheels, of a work supporting mechanism for presentation of work in the grinding throat between said grinding and regulating wheels including a supporting bracket, a work rest blade carried by the bracket, means for securing the blade in adjusted position as respects the bracket, outboard supports carried by the bracket including a series of supporting arms, rollers adjustable on the arms for alignment with the work supporting plane of the work rest blade, additional arms carried by the bracket, work supporting rollers on the arms, and means for adjusting the second series of rollers for engagement with the work at circumferentially spaced points from the first series of rollers in correspondence with the circumferential spacing between engagement of the work rest blade and the regulating wheel with the work.

2. A machine of the character described including opposed grinding and regulating wheels forming a work receiving throat there between, means for varying the width of said

throat, work supporting means disposed within the throat and exterior to the throat for corresponding engagement with a work piece to support same against the thrust of the grinding wheel, means for correspondingly adjusting said several work supporting members to maintain their simultaneous contact with the work piece along a predetermined radial plane thereof, additional supporting members exterior to the throat and means for adjusting the additional supporting members to present the contacting portions thereof in contact with a radial plane of the work passing through a point of engagement of the regulating wheel with the work.

3. The combination with a centerless grinder including opposed grinding and regulating wheels for simultaneous engagement with a work piece, a work rest blade in the throat between the wheels for supporting a work piece in joint engagement with said wheels, outboard supports, a series of work supporting members carried by the outboard supports in underlying relation to the work piece in correspondence to the relation of the work rest blade thereto, and an additional series of laterally disposed work rest supports in opposition to the first series for engagement with the work piece in correspondence to the engagement of the regulating wheel therewith at the throat.

4. The combination with a centerless grinder including grinding and regulating wheels forming a work receiving throat there between, of a bracket disposed within the throat, a work rest blade supported by the bracket and projecting in position to engage and support a work piece in the throat, lateral projections carried by the bracket, a series of work supporting members carried by the projections and extending in parallel relation to the work rest blade and a second series of angularly related work supporting members carried by the projections for cooperation with the first series.

5. The combination with a centerless grinder including grinding and regulating wheels forming a work receiving throat there between, of a bracket disposed within the throat, a work rest blade supported by the bracket and projecting in position to engage and support a work piece in the throat, lateral projections carried by the bracket, a series of work supporting members carried by the projections and extending in parallel relation to the work rest blade, a second series of angularly related work supporting members carried by the projections for cooperation with the first series, and means for angularly adjusting the members of the second series with respect to the members of the 1st series to vary the engagement of the second series with an interposed work piece.

6. The combination with a centerless

grinder including opposed grinding and regulating wheels, an intermediate work rest, lateral projections carried by the grinder, work supports mounted in pairs on the projections, work supporting rolls carried by the members of each pair, means for radially adjusting the series with respect to the projections, and additional means for varying the separation of the rolls of an individual 10 pair.

7. A centerless grinding machine including a bed or support, a grinding wheel mounted thereon, a slide mounted on the bed and movable in a direction toward and from the 15 grinding wheel, a regulating wheel unit and a bracket carried by the bed for relative movement as respects each other and for joint movement toward and from the grinding wheel, a work rest blade centrally mounted 20 on the bracket, cylindrical supports laterally projecting from the bracket, work supporting units mounted in pairs on the supports, means for securing one member of each pair against rotation on the support, 25 and additional means for locking the other member of the pair in circumferentially adjusted position on the support.

8. A centerless grinding machine including a bed or support, a grinding wheel mounted 30 thereon, a slide mounted on the bed and movable in a direction toward and from the grinding wheel, a regulating wheel unit and a bracket carried by the bed for relative movement as respects each other and for joint 35 movement toward and from the grinding wheel, a work rest blade centrally mounted on the bracket, cylindrical supports laterally projecting from the bracket, work supporting units mounted in pairs on the supports, 40 means for securing one member of each pair against rotation on the support, additional means for locking the other member of the pair in circumferentially adjusted position 45 on the support, and cooperating means on the members of each pair for determining their relative angular adjustment.

9. A centerless grinding machine including a bed or support, a grinding wheel mounted thereon, a slide mounted on the bed 50 and movable in a direction toward and from the grinding wheel, a regulating wheel unit and a bracket carried by the bed for relative movement as respects each other and for joint movement toward and from the grinding 55 wheel, a work rest blade centrally mounted on the bracket, cylindrical supports laterally projecting from the bracket, work supporting units mounted in pairs on the supports, means for securing one member of each pair 60 against rotation on the support, additional means for locking the other member of the pair in circumferentially adjusted position on the support, said members including extensible arms, work supporting rollers carried by the arms and means for securing the

rollers in desired radially adjusted position as respects the cylindrical support therefor.

10. The combination with a centerless grinder including opposed grinding and regulating wheels forming a grinding throat 70 therebetween, of a bracket subtending the grinding throat and supporting a work rest blade within the grinding throat, support bars extending from opposite sides of the bracket, outboard roller supports carried by 75 the supporting bars and comprising a pair of arms, means securing the arms in adjusted positions radially of the supporting bars, and contact rollers carried by the arms in alignment with the work rest blade and point of contact of the regulating wheel with the work whereby the work on one side of the grinding throat is supported parallel with the throat for movement therewith into the throat and whereby the work on the other 80 side of the grinding throat is supported parallel with the throat for movement therewith after it passes through the said throat.

11. In a centerless grinder the combination of a pair of opposed grinding and regulating wheels forming a grinding throat 90 therebetween, a work rest blade subtending the grinding throat for supporting work in engagement with the grinding and regulating wheels and a work supporting trough 95 exterior of the grinding throat comprising a supporting bar, a plurality of work supporting units carried by the bar in spaced relation, each work supporting unit comprising a pair of arms one of which has a split clamping collar surrounding the bar and a lug extending therefrom, the other arm having a split clamping collar and an ear extending therefrom overlying the lug, adjusting means extending through the ear and contacting the lug for adjusting the arms relative to one another about the supporting bar, means contracting the split collars to secure the arms to the bars in their adjusted positions, and work contacting rollers carried by the arms at the 100 upper end thereof.

12. In a centerless grinder the combination of a pair of opposed grinding and regulating wheels forming a grinding throat 115 therebetween, a work rest blade subtending the grinding throat for supporting work in engagement with the grinding and regulating wheels and a work supporting trough 120 exterior of the grinding throat comprising a supporting bar, a plurality of work supporting units carried by the bar in spaced relation, each work supporting unit comprising a pair of arms one of which has a split clamping collar surrounding the bar and a lug extending therefrom, the other arm having a split clamping collar and an ear extending therefrom overlying the lug, adjusting means extending through the ear and contacting the lug for adjusting the arms relative to one 125 130

another about the supporting bar, means contracting the split collars to secure the arms to the bars in their adjusted positions, work contacting rollers carried by the arms at the upper end thereof, and means for adjusting the rollers relative to the supporting arms.

6 In testimony whereof I affix my signature.

JOHN E. CASTER.
